UNITED STATES PATENT OFFICE.

JOSEPH V. ROBINSON, OF WASHINGTON, DISTRICT OF COLUMBIA.

AUTOMATIC TRAIN-PIPE COUPLING.

1,245,780.

Specification of Letters Patent.

Patented Nov. 6, 1917.

Application filed December 23, 1912. Serial No. 738,398.

To all whom it may concern:

Be it known that I, JOSEPH V. ROBINSON, a citizen of the United States, residing at Washington, District of Columbia, have invented certain new and useful Improvements in Automatic Train-Pipe Couplings, of which the following is a specification.

The present invention relates to couplers for automatically connecting the steam and railway couplings when coupling the cars together.

The object of the invention is to improve and simplify the structure of such couplers and to render them efficient and durable. The various improvements constituting the invention will be described in detail in connection with the accompanying drawing, in which:

Figure 1 is a side elevation partly in section of a train pipe coupler embodying the present invention, and showing in side elevation a removably connected interchange coupling.

Fig. 2 is a rear view of the coupling head and connected parts shown in Fig. 1, the spring being broken away and the axial supporting rod shown in section.

Figs. 3 and 4 are side and rear views of the interchange couplers shown in Fig. 1. Fig. 5 is a detail of the attaching means for the interchange coupler.

Fig. 6 is a plan view of the couplers shown in Fig. 1, partly in horizontal section. Fig. 7 is a front view of the base and bearing plate for the spring.

Fig. 8 is a rear view of the base. Fig. 9 is a sectional view of another form of fluid conduit, adapted to be seated in the head and provided with a detachable coupling member.

Fig. 10 is a front view of a portion of the conduit member shown in Fig. 9.

Referring to the drawings, a one-piece base A is secured to the lug or bracket 12 by bolts 13, the bracket being in turn connected to the usual coupler (not shown) of the car. To permit adjustment of the base

along the bracket, the bracket is provided with an elongated slot, as shown, across the inner walls of which extend ribs 13' that prevent accidental slipping of the base on the bracket. The body 14 of the base is cup-shaped and has a partly spherical seat 15 formed at its bottom in which seat a

55 circular plate 16 having a convex partly spherical portion 17 is mounted for univer-

sal movement. The plate 16 is perforated at 18 to permit it to rock about a rod 19, and its edge is turned in forming a flange 20. Within the flange and in close engagement therewith the base coil of a conical spring 21, coiled of a round tapered bar, is secured for movement with the plate 16. The forward or smaller end of the spring is seated in an annular seat 23 on the rear face of the member 22. The spring is maintained in position under a slight compression by a gradually tapered resilient rod 19 which extends through the base A, the perforation 18 of the plate 17 and the spring 21 and has its small end rigidly connected at 24 to the member 22 on which member is mounted the pin-and-funnel coupling head B. (See Fig. 6.) The rod 19 is rectangular in cross section and tapers abruptly at the rear for a short distance, producing a head or enlarged end 25 which in the normal position rests in a correspondingly shaped socket 26 of a projection 27 centrally located on the rear face of the body 14 of the base A.

The engagement of the head 25 of the rod with the socket 26, and the positive connection of the small end of the rod with the member 22, prevents excessive forward movement of the coupling head B in service and holds the conical spring 21 under slight compression as stated. This always brings the head 25 of the rod into proper register with the socket 26, and insures correct positioning of the coupling head B for coupling. The rectangular tapering shape of the socket, and corresponding tapering of the rod, prevent turning of the latter in the base A from the normal position, whereby it resiliently resists rotary movement of the coupling head B. As the cars couple, the rod 19 moves rearwardly to the position shown in Fig. 6 in which position the coupling head B may move freely in any lateral direction, and the head may also rotate freely within certain limits as the rod 19 will then fit loosely in the smaller end of the socket 26.

This arrangement provides an improved construction of high efficiency in which the coupling head B is supported for free universal movement from the normal uncoupled position solely by the resilient rod 19, the latter operating to move out of engagement with the base A and free it of such supporting strains as the cars couple. In this manner a wide range of movement is allowed the

head B in the coupled position, resisted only by the frictional resistance occurring between the engaging surface of the plate 17 and base A, thereby almost entirely eliminating the distorting strains on coupled heads, incident to the quick vibrating movement of running cars.

The fluid-conducting member 22 extends through, and, as stated, carries the coupling head B which has the usual pin-and-funnel guiding means 28 and 29 and an air extended gasket 30 at its face. The rear end 31 of the member is angularly disposed to the longitudinal and transverse center lines 15 of the head B and is threaded as shown to detachably receive the nipple of the usual train pipe hose on the car being equipped. The fitting is maintained in this angular position by the ribs or projections 32 and 33 20 of the head B, (see Fig. 2), which ribs constitute means for positioning the member.

An interchange coupling comprising a head 34 having a perforated face 35 is positively connected to the head B by the claws 25 or hooks 36 on the face of the interchange and the pins 37 which extend through the head B and into the fluid-conducting member 22 on opposite sides of the latter. The claws are slightly inclined at 38 as shown 30 in Fig. 5 to draw the face of the interchange coupling tightly against the face of the fluid-conducting member 22 so as to compress the gasket 30 therein and make a tight joint. A slight rotation of the interchange coupling 35 when assembling on the head B produces this clamping effect and brings the face 39 of its head 34 into position, angularly disposed to the vertical and horizontal axes of the coupling head B as indicated in Fig. 2. 40 When thus assembled the nipple in the end of the train pipe hose of the car to be put in interchange is coupled into the head 34 of the interchange coupling for efficient operation. This arrangement produces a compact 45 and durable means for interchangeably connecting a train pipe hose of a car to the coupling head B.

In Figs. 9 and 10 is shown a modification of the fluid-conducting member 22 in which 50 the inner end of the member comprises an ordinary non-automatic hose coupling 40. With this construction the coupling in the end of the train pipe hose of the car equipped with the automatic device is coupled into 55 the coupling 40 for automatic operation and when it is desired to make interchange, disconnected therefrom and passed under the guide pin 28 of the head B and connected to the hose of the unequipped car.

60 In the foregoing specification I have described the best embodiment of the invention in point of service, but I desire it understood that the invention is not limited to the particular structure shown and described. Should a more flexible support for

the coupling head B be found desirable, the smaller end of the resilient rod 19 may be connected to the head in such wise as to allow movement of the head B about such end in both the uncoupled and coupled position or 70 either one thereof. Greater resiliency may also be produced by mounting the apex end of the conical spring 21 in an oscillating plate on the rear face of the member 22 or head B similar to the manner in which the 75 base of the spring is mounted in the base A.

Having thus described the invention what is claimed as new is:

1. In an automatic train pipe coupling, the combination with a car coupler carrying 80 a supporting bracket having a slot, of a coupler supporting base, and a bolt passing through said slot for securing the base to the bracket, the walls of the slot being ribbed to prevent shifting of the base longitudinally 85 of the bracket.

2. In an automatic train pipe coupling, the combination of a car coupler provided with a bracket having a slot, a coupling head, a supporting base for said head, means 90 in said slot for clamping said base to said bracket, and a rib extending across the wall of said slot in the transverse horizontal plane to prevent shifting of said base longitudinally of said slot. 95

3. In an automatic train pipe coupling, the combination of a base, a coupling head, and means for supporting the head from the base, said means positively engaging the base to prevent lateral movement of the head 100 only when the latter is in uncoupled position.

4. In an automatic train pipe coupling, the combination of a base, a coupling head, and means for supporting the head from the 105 base, including a stem extending from the head to the base and positively engaging the latter to prevent lateral movement of the head only when it is in uncoupled position.

5. In an automatic train pipe coupling, 110 the combination of a coupling head, a base, means acting against said base at all times to place said head under pressure, and means for supporting said head so as to permit movement thereof laterally of the car in the 115 horizontal plane and for resisting such movement from the normal uncoupled position only.

6. In an automatic train pipe coupling, the combination of a coupling head, a base, 120 means acting against said base at all times for extending and placing said head under pressure, and means for supporting said head so as to permit lateral movement thereof and for resisting such movement from 125 the normal uncoupled position only.

7. In an automatic train pipe coupling, the combination of a coupling head, a base, means acting against said base at all times for extending said head, and means engag- 130

- ing the base for supporting the head and preventing lateral movement in the horizontal plane from the normal uncoupled position, said means being freed from such engagement with the base as the cars couple.
8. In an automatic train pipe coupling, the combination of a coupling head, means for placing said head under pressure, and separate resilient means for yieldingly supporting said head against lateral movement in any direction from the uncoupled position, said resilient means constituting the sole support of said head when in such position.
15. 9. The combination of a coupling head, a base, resilient means acting to extend the head, and a resilient rod interposed between said base and head constituting the sole support for the latter.
20. 10. In an automatic train pipe coupling, the combination of a coupling head, a base, resilient means acting to extend the head, and a resilient rod extending through said base auxiliary of said means and connected 25 with the head for supporting the latter.
11. In an automatic train pipe coupling, the combination of a coupling head, a base, and a straight resilient rod extending forwardly of said base for supporting said 30 head and for resisting rotary movement thereof.
12. In an automatic train pipe coupling, the combination of a coupling head, means for extending said head, a base, and a resilient rod projecting from said base axially of said extending means for supporting said head.
35. 13. In an automatic train pipe coupling, the combination of a coupling head, means 40 for extending the head, a base, and a rod extending slidably through said base for supporting the head with a greater resistance to lateral movement thereof from the uncoupled than from the coupled position 45 of said head.
14. In an automatic train pipe coupling, the combination of a coupling head, a base, a spiral spring interposed between said head and base and having its rear end movable 50 relative to the base, and a rod extending through said base and axially of said spring for supporting said head, said rod engaging the base to oppose lateral movement when the head is in uncoupled position and being freed from such engagement as the cars couple.
15. In an automatic train pipe coupler, the combination with a base and a coupler head, of resilient means between the base and head and serving to extend the head, 60 and a flexible rod movably seated in the base and serving as the sole support of the head when in uncoupled position.
16. In an automatic train pipe coupler, the combination with a base and a coupler 65 head, of a spiral spring between the base and head and serving to extend the latter, and a rod connected to the head and extending through said spring and through the base, for yieldingly maintaining said head 70 in the normal uncoupled position.
17. In an automatic train pipe coupler, the combination with a base and a coupler head, of a spiral spring between the base and head and serving to extend the latter, 75 and a rod connected to the head and extending through said spring and through the base and operating to support the head, said base having a rearwardly flaring socket and said rod having a head adapted to seat in 80 said socket.
18. In an automatic train pipe coupler, the combination with a base and a head, of a spring interposed between the base and the head, a universally movable seat in the 85 base to receive the spring, and a rod connected to the head extending through the spring and the base, said base having a rearwardly flaring socket and said rod having a head adapted to seat in said socket against 90 lateral movement.
19. In an automatic train pipe coupling, the combination of a base, a spiral spring having one end seated on the base, a coupling head mounted on the other end of the 95 spring, a fluid conduit in the head extending from a substantially centrally arranged port in the forward face to a port at one side of the seat on the rear face which receives the supporting spring, and supplemental means 100 between the base and head for limiting relative lateral movement.

In testimony whereof I affix my signature in presence of two witnesses.
